UNITED STATES PATENT OFFICE

EDWARD S. PETERSON, OF CHICAGO, ILLINOIS, ASSIGNOR, BY MESNE ASSIGNMENTS, TO ASSOCIATED ELECTRIC LABORATORIES, INC., OF CHICAGO, ILLINOIS, A CORPORATION OF DELAWARE

TELEPHONE SYSTEM

Application filed July 7, 1930. Serial No. 465,901.

This invention relates in general to telephone systems and in particular to automatic telephone systems in which connections may be established through the medium of subscriber controlled step-by-step switches. More particularly the invention is concerned with a system of the above character which is combined with or has superimposed on it, so to speak, a special signalling or messenger call service system; and the broad object of the invention may be said to be the provision of new and improved auxiliary apparatus for use in connection with a telephone system.

It is an object to provide a telephone system in which certain subscribers in addition to being able to establish regular telephonic service with other subscribers, may, by dialing a special number signal a telegraph office, thereby dispensing with the usual messenger call boxes which require separate lines to the telegraph office.

A special object is the provision of means whereby all subscribers provided with the special services may dial the same particular number and immediately upon hearing a tone, replace the receiver, whereupon the auxiliary equipment operates to permanently record the number of the calling subscriber at the telegraph office, so that a messenger may be dispatched to the subscriber.

A feature of the invention resides in providing a special "booster" battery connection back over the switch train of the connection, when a subscriber calls the special number, in order to initiate the operation of the auxiliary apparatus.

Another feature resides in providing a group of relays individual to each special subscriber, which operate to control the auxiliary apparatus in a manner to make a record of the number of the associated subscriber at the telegraph office.

The above objects and features, together with others which will be apparent hereinafter, will now be described in detail, reference being had to the accompanying drawings comprising Figs. 1, 2 and 3 which show by means of the usual circuit diagrams sufficient of the apparatus employed in a system

embodimenting the principles of the invention to enable the same to be easily understood.

Referring to the drawings, which should be placed with Fig. 2 to the right of Fig. 1 and Fig. 3 below Fig. 2, the subscribers' substations A and A' Fig. 1 are the ordinary automatic substations having the usual talking, signalling and impulse transmitting instrumentalities. The lineswitches LS and LS' are mechanically of the well known rotary type in which the wipers have no normal position and move in a forward direction only. The selector switch S and the connector switch CN, shown in skeleton form, are mechanically of the well known Strowger vertically and rotary type in which the bank contacts are arranged in horizontal rows or levels. The group of relays RG is one of a number which are seizable by the selector S when its wipers are raised to a special level of bank contacts.

Fig. 2 shows two groups of relays, SR1 being individual to substation A and SR6 individual to substation A'. These relay groups start the operation of the auxiliary apparatus and also determine the three-digit number or code of the associated substation which is to be transmitted to the telegraph office. The cut-off switch CO determines the number of times the code is to be sent to the telegraph office and is a rotary step-by-step switch in which the wipers move only in a forward direction each time the armature of its magnet retracts its armature.

Fig. 3 illustrates the code sender switch CS which is of the same construction as the cut-off switch CO. This code sender switch together with the associated group of control relays operates to transmit the three digit code or number of a calling substation, over a trunk line extending to the telegraph office where the punch register PR is operated.

The system having been described in general a detailed description will now be given of its operation. For this purpose it will be assumed that the subscriber at the substation A desires to establish an ordinary telephone connection with the subscriber at substation A'. Upon the removal of the receiver at the substation A a circuit is completed for line

relay 15 of the lineswitch LS and over the line conductors 5 and 6. Line relay 15 upon energizing closes a circuit for the switching relay 10 and rotary magnet 25 in series at armature 16, and at armature 17 connects the test wiper 19 to a point midway between the switching relay 10 and stepping magnet 25. A branch of the ground circuit from armature 16 extends over conductor 14 to the connector bank to maintain the line busy at this time. A branch of conductor 14 extends to relay 100 of Fig. 2, but due to its high resistance it cannot energize at this time. From this point the operation depends upon whether the selector S or other selectors connected to the bank contacts of the lineswitch LS are busy or idle. If the selector with which wiper 19 is engaged is busy, ground will be extended over wiper 19, armature 12 and its back contact, armature 17 and its front contact, back contact of armature 26, through the winding of the stepping magnet 25, to battery. The switching relay 10 is thereby short-circuited and the stepping magnet 25 is operated in the manner of a buzzer to rotate the wipers 18, 19 and 20 over their associated bank contacts. As soon as an idle selector, such as S, is encountered, ground potential will no longer be present on the test wiper 19, and therefore the switching relay 10 is no longer short-circuited and it energizes in series with the stepping magnet 25. However, owing to the high resistance of the switching relay 10, the stepping magnet does not operate in series with it. Switching relay 10 upon energizing disconnects the test wiper 19 from its armature 12 and its back contact and connects it directly to the private normal conductor 14.

As a further result of its energization switching relay 10 disconnects the circuit of the line relay 15 from its armatures 11 and 13 and then connects the line conductors 5 and 6 directly through to the wipers 18 and 20, and over conductors 21 and 23, armatures 51 and 54 and their back contacts to battery and ground through the upper and lower winding of line relay 30 of the selector S. Line relay 30 upon energizing closes a circuit for slow-release relay 35 from its armature 31 to ground at armature 53. At armature 36 relay 35 upon energizing extends ground over the release trunk conductor 22 to render the selector busy, and at armature 37 the circuit for series relay 40 and vertical stepping magnet 55 is prepared.

The calling subscriber A now operates his calling device S in accordance with the first digit of the desired number, thereby producing a series of interruptions in the circuit of the line relay 30 of the selector S. As soon as the line relay deenergizes in response to the first of these interruptions it completes a circuit from ground on armature 53, armature 31 and its back contact, armature 37 and

its front contact, through the winding of the series slow-release relay 40 and the winding of the stepping magnet 55, to battery. Slow-release relay 40 and the stepping magnet 55 energize in series over this circuit and the vertical magnet upon operating raises the wipers 61, 62 and 63 of the selector one step opposite its first level of bank contacts, whereupon the off-normal springs 58 and 60 immediately operate. As a result of the closure of the off-normal spring 58 a circuit is completed from ground at release conductor 22, armature 41 and its front contact, through the off-normal springs 58, contacts 57, through the winding of the stepping relay 45, to battery. At armature 46 relay 45 completes a locking circuit for itself and at armature 47 prepares a circuit for the rotary magnet 56. Relay 40 remains energized as also does relay 35 between impulses of a series.

The remaining impulses of the series operate the vertical magnet 55 to raise the wipers opposite the desired level of bank contacts, and shortly after the last impulse slow-release relay 40 will deenergize and close a circuit for the rotary magnet 56 and its armature 41. Rotary magnet 56 upon energizing rotates the wipers 61, 62 and 63 into engagement with the first set of bank contacts of the level, and at its armature 57 opens the circuit for the stepping relay 45. Stepping relay 45 upon deenergizing opens another point in its circuit at armature 46, and at armature 47 opens the circuit of the rotary magnet 56, and this magnet upon deenergizing again closes its armature 57 to prepare a new circuit for stepping relay 45.

From this point the operation depends upon whether the first trunk line terminating in the first set of contacts in the bank is busy or idle. If it is busy stepping relay 45 energizes again over a circuit extending from ground by way of the test contact with which wiper 62 is in engagement, armature 52 and its back contact, closed off-normal springs 58, armature 57 and through the winding of relay 45, to battery. This relay upon again energizing closes a locking circuit for itself at armature 46 and at armature 47 again completes a circuit for rotary magnet 56. This alternate operation of the stepping magnet and the rotary magnet continues so long as test wiper 62 engages grounded contacts.

I will now assume that the trunk line extending to the connector switch CN is idle, and that being the case the wipers 61, 62 and 63 of the selector will arrive on bank contacts 67, 68 and 69 as there is no longer ground potential upon contact 68 the stepping relay 45 no longer energizes. The switching relay 50 is no longer shunted and it energizes from ground on the release trunk conductor 22, through the winding of switching relay 50, off-normal contacts 58, armature 57 and in series through the winding of the relay 45.

to battery. The stepping relay 45, however, does not energize in this circuit due to the high resistance of switching relay 50. Relay 50 upon energizing removes ground from 5 armature 53 so that slow-release relay 35 will deenergize, and at armature 52 disconnects the test wiper 62 from the point between the switching relay 50 and stepping magnet 45 and connects it instead to ground by way of 10 the release trunk conductor 22 at armature 36, thus making the trunk line busy immediately, and at armatures 51 and 54 disconnects the trunk conductors 21 and 23 from the 15 windings of line relay 30 and extends them by way of the front contacts of these armatures, wipers 61 and 63, bank contacts 67 and 69, over the trunk conductors to the line relay of the connector CN. The connector CN thereupon operates and places ground upon 20 the release trunk conductor 22 to establish the usual holding circuit for the selector S and the lineswitch LS before slow-release relay 35 of the selector S has time to deenergize.

25 The calling subscriber now operates the calling device S in accordance with the second digit of the called number. The connector CN is thereby operated to raise its wipers to the desired level of bank contacts. The 30 subscriber then dials the third or final digit of the called number and as a result the connector rotates its wipers into connection with the line extending to substation A', and in the usual manner upon the completion of 35 the connection the called line is signalled to notify the subscriber that he is wanted. When the called party answers the conversation will proceed and when it is completed the subscribers will replace their receivers, bringing 40 about the release of the connection in the usual manner. As the foregoing operation of the connector switch CN is well understood it is not thought necessary to further describe its operation in detail, except to state 45 that upon the release of the connection the connector switch CN removes the holding ground from release trunk conductor 22, which likewise opens the circuit of the switching relay 50, so that this relay upon de- 50 energizing will close a circuit from armature 53 through armatures 31 and 37, off-normal springs 60 and then through the winding of the release magnet 59, to battery. The release magnet upon energizing restores the wipers 55 of the selecting switch S to normal. The lineswitch LS is also restored to normal by removing the ground from the release trunk conductor 22 which held the switching relay 10 energized and as ground is no longer en- 60 countered on the busy guarding circuit 14 the subscriber at substation A is available for any incoming calls.

65 The foregoing describes an ordinary telephone connection which may be established between any two subscribers in the system,

and in order to further describe the system a description of the operation will now be given wherein the subscriber at substation A requires the services of a messenger, and therefore desires to signal the telegraph office Fig. 70 3 without actually engaging in any conversation. For this purpose he will operate his calling device S in accordance with a special three digit number which same number will be dialled by any of the subscribers in the 75 system having the messenger service available or who subscribes for this service.

Upon the removal of the receiver at the substation A the lineswitch LS operates, as has been explained, to seize an idle selector 80 switch S and when one has been found the subscriber dials a particular number so that the wipers of the selector are elevated opposite a particular level of bank contacts, over one of which a number of relay groups, such 85 as RG, may be reached. When an idle relay group, such as RG, has been seized by the selector S the wipers 61, 62 and 63 will be positioned upon bank contacts 64, 65 and 66, and the relay 75 will become energized from bat- 90 tery through its upper winding, line conductor 21, line conductors 5 and 6, of the substation A, line conductor 23, through the lower winding of relay 75, to ground, through the primary winding of the tone machine T. 95 The subscriber at substation A will hear a tone in his receiver, which is generated by the tone machine T, and thereby become aware of the fact that his line has been connected with the auxiliary signalling equipment and that 100 the telegraph office will be signalled for a messenger who will be promptly dispatched to the subscriber's premises. If the subscriber after hearing the tone, desires, he may immediately replace his receiver upon the 105 switchhook, thereby automatically releasing the selector switch S and the lineswitch LS to normal, so that this equipment will be available for other calls or for another call by the same subscriber to another subscriber. 110

Relay 75 of the relay group RG upon energizing, at its armature 76 and its front contact closes a locking circuit for itself from ground at alternate front contacts of armature 81 so that this relay will remain 115 energized in case the subscriber A should immediately replace his receiver and release the connection upon hearing the tone from the tone machine T. As a further result of the energization of the relay 75 it attracts 120 its armature 77. This armature, it may be explained, is of a type which has a weight attached to one end of it so that it will vibrate for a certain length of time before coming completely to rest onto its front contact, 125 whereupon a circuit is completed from ground through this armature, through the winding of slow-to-pull-up relay 80, to battery. At armature 78 and its front contact, relay 75 momentarily connects the "booster" 130

battery B to the conductor 90. This booster battery B, it may be explained, is of slightly higher voltage than the ordinary batteries indicated on the relays in the drawings and 5 has the effect of boosting or assisting these batteries. This booster battery is thereby extended momentarily through the resistance, the alternate contacts of armature 78, conductor 90, bank contact 65 and wiper 62 10 which is resting upon it, armature 52 and its front contact, release trunk conductor 22 extending through the selector S, wiper 19 of the line switch LS, armature 12 and its front contact, conductor 14, (which is grounded 15 when the switches are in use to prevent other calls from coming in on them over conductor 14) Fig. 2, through the winding of high resistance relay 100, to battery. The high resistance relay 100 ordinarily will not energize from ground over the release trunk conductor 14, but as in this instance the booster battery B is connected to this conductor this relay will energize.

Referring back to the operation of slow-to-energize relay 80, the armature 82, after armature 78 has been completely attracted and disconnected the booster battery B from its alternate contacts, will extend ground to release trunk conductor 90 to maintain the 20 relay group RG in a busy condition. At armature 81, relay 80 disconnects the locking ground from relay 75, so that if the subscriber has released the connection it will become deenergized and at armature 77 upon 25 falling away open the circuit of slow-to-energize relay 80 and when this relay retracts its armatures the relay group RG will now be in its original normal position.

Referring now to Fig. 2 it may be stated 30 that the relay group SR1 is individual to the subscriber at substation A while the relay group SR6 is individual to the substation A' and a relay group, such as SR, is therefore individual to each station in the 35 telephone system which has available the messenger call service. The multiple conductors 128, 129, 130, 131 and 132 extending to the top of this figure connect to similar relay groups in the same manner as the relay groups SR1 and SR6, and the purpose of 40 these relay groups it may be stated is to set up a number which is individual to its associated substation on the banks of the code sender CS, Fig. 3. Another purpose 45 is to prevent the operation of the code sender CS by any other relay group, such as SR6, while the code number of one substation is being transmitted to the telegraph office. In other words the equipment temporarily 50 stores up the code number of its associated substation until the code sender and its auxiliary equipment is available.

Returning now to the operation of the high 55 resistance relay 100 of the station relay group SR1, it will be recalled that this relay was

energized momentarily from the "booster" battery B extending over a circuit from the relay group RG, through the selector S and the lineswitch LS and over the conductor 14. At grounded front contact of armature 101, 70 relay 100 completes a circuit through the winding of relay 105 to battery, and this relay upon energizing closes a locking circuit for itself extending from ground on back contact and armature 113, front contact and armature 108, through the winding of the relay to battery, so that this relay remains locked up even though the high resistance relay 100 is deenergized, due to the hanging up of the receiver at the subscriber's station 80 A. At front contact and armature 107, relay 105 prepares a circuit for relay 110 and at armature 106 and its back contact it opens a chain circuit extending in series through all of the station relay SR groups, so as to 85 prevent any other station from operating the code sender equipment while the code of the instant station is being transmitted. At front contact and armature 106 a circuit is prepared for relay 115, extending from battery through the resistance at armature 141 and its back contact, conductor 130, upper winding of relay 115, armature 111 and its back contact, front contact and armature 106, conductor 132, to ground at back contact and armature 157. Relay 115 accordingly energizes over this circuit and completes a locking circuit for itself through its lower winding, extending from ground on back contact and armature 113, armature 117 and its front contact, lower winding of relay 115, conductor 131, through the winding of relay 140, to battery. At its armature 116 relay 115 prepares a circuit for relay 110, 90 while at its armatures 118, 119 and 120 and their associated front contacts the particular or special code number 384 assigned to substation A is set up on the bank contacts of the code sender CS, by way of the conductor 128.

At the time relay 140 energized it completed an obvious circuit at front contact and armature 141 for relay 145, and this relay upon energizing closes ground from its front contact and armature 146 over conductor 142, through the winding of relay 225, to battery, 111 Fig. 3.

Before proceeding further with a detailed description of the apparatus and code sender of Fig. 3 it may be stated that this switch is mechanically of the same construction as the cut-off switch CO, in that the stepping magnet 240 rotates the wipers 250, 251, 252 and 253 in a forward direction step-by-step over their associated bank contacts. The arrangement of the bank contacts and the wipers is such that a pair of wipers, such as wipers 252 and 253, simulate a 50 point switch and in order to reduce the cost a standard 25 point bank has been provided in each case, and the operation is such that im- 125

mediately upon the wiper 253 moving onto its first bank contact 259 the wiper 252 will be leaving the last one, and when wiper 252 engages bank contact 258 wiper 253 will step off of its last bank contact. The wipers 250 and 251 are arranged in a similar manner. The first half of the bank contacts over which wiper 253 rotates is arranged to pick-up the first digit of the code number, while the last half of this bank will pick-up the second digit of the code number. Similarly wiper 252 will engage a particular bank contact in the first half of its bank to pick-up the third and final digit of the code number. In actual practice the code digit conductors extending from the bank contacts over which wipers 252 and 253 rotate would be connected to an intermediate distributing frame, so that the code conductors extending from the station relay group, such as SR, could be cross connected for any desired number. In this manner additional stations may be added or existing ones changed as desired. In accordance with the above for the purpose of illustration the station relay group SR1 is arranged to set up the code digit number 384 on the bank contacts of the code sender. Conductor 121 therefore extending to digit number 3 on the first half of the bank over which wiper 253 rotates, conductor 122 extending to code digit conductor 8 in the last half of the bank, while conductor 123 extends to number 4 code digit conductor in the first of the banks over which wiper 252 rotates. In a similar manner the station relay group SR6, which is individual to substation A' is arranged to set up the code number 965 on the banks of the code sender.

Returning now to the operation of relay 225 of Fig. 3 at the time it was operated from ground on armature 146 of relay 145, this relay upon operating prepares a circuit for slow-release relay 230 at armature 228, at armature 229 it prepares a shunting circuit for relay 220, while at armature 219 it prepares a circuit for starting the code sender switch CS extending over armatures 226 and 227 as will now be pointed out; ground on armature 219 and its front contact, armature 226 and its front contact, wiper 253 and bank contact 259 upon which it is normally resting, armature 227 and its front contact, through the winding of relay 220 and the non-inductive resistance, to battery. Relay 220 upon energizing closes a locking circuit for itself over its front contact and armature 221 to ground at armature 219, while at armature 222 it prepares a circuit for operating the printing recorder PR at the telegraph office over conductors 223 and 224. A branch of the circuit extending from ground at armature 219 and its front contact, likewise, extends to armature 216 and its back contact, through the winding of slow-to-energize relay 210, to battery. The battery through the

resistance extending to the other side of the winding of this relay is for the purpose of making this relay a slight amount slower to pull-up, because part of the current is shunted through the resistance and also for preventing excessive sparking at armature 216. After an interval the relay 210 closes its armature 211 onto its front contact and completes the circuit for slow-to-energize relay 205.

Relay 205 upon operating closes its armature 206 onto its front contact and completes a circuit extending from ground at armature 219 and its front contact, armature 206 and its front contact, armature 231 and its back contact, back contact and armature 232, through the winding of relay 215, to battery. Relay 215 upon energizing opens the circuit of slow-to-pull-up relay 210 at back contact and armature 216. Relay 210, after an interval deenergizes and opens the circuit for slow-to-pull-up relay 205 at armature 211, and after a slight interval relay 205 retracts its armature 206, so that the circuit for relay 215 is interrupted. Relay 215 upon falling away again completes a circuit for slow-to-pull-up relay 210 and the cycle of operation is again repeated, as long as armatures 231 and 232 remain at normal. Each time that relay 215 energizes it completes a circuit over the trunk conductors 223 and 224 to the printing recorder PR at the telegraph office, from ground on armature 219 and its front contact, armature 216 and its front contact, front contact and armature 222, trunk conductor 223, through the winding of the printing recording relay PT, back over trunk conductor 224, to battery at the exchange. Each time the printing recording magnet PR energizes it operates its armature to print a dot or make a perforation in the moving tape. Each perforation corresponds to an impulse and a series of these perforations will correspond to a particular number or digit of the code. The operation of this printing recorder is well known in the art and it is not thought necessary to further describe its operation.

A branch of the original energizing circuit of relay 215 extends by way of the back contacts of armatures 231 and 232, through the winding of the stepping magnet 240, to battery, so that each time the relay 215 is energized the stepping magnet 240 likewise receives an impulse of current. Accordingly, when slow-release relay 205 releases its armature 206 the circuit for stepping magnet 240 is opened and it retracts its armature, thereby rotating each of the wipers 250, 251, 252 and 253 in a forward direction one step onto the first or next set of bank contacts. The wipers 252 and 250 will not be effective at this time due to the fact that they will be rotating through an arc in which there are no bank contacts. However, wipers 251 and 253 will

130

step onto their second bank contact. The second bank contact upon which wiper 251 is now resting is grounded but this has no effect at this time because relay 225 is energized and maintains armature 228 away from its back contact. As the wiper 253 is now resting on its second bank contact the conductor #1 connected to this bank contact has no potential connected to it at this time and 10 no action takes place. Accordingly, the stepping magnet 240 continues to rotate the wipers step-by-step under control of the repeated slow operations of the relays 205, 210 and 215, until wiper 253 reaches the fourth 15 bank contact connected to #3 conductor or conductor 121 which represents the first digit of the code number of the operated substation A. During this interval as the wipers are rotated one step at a time across the bank 20 contacts, relay 215 operates in synchronism and sends an impulse of current over the trunk line to the telegraph office to operate the printing recorder three times.

When wiper 253 reaches the bank contact 25 to which the #3 conductor or conductor 121 is connected, a circuit is completed extending from ground at armature 219 and its front contact, armature 226 and its front contact, wiper 253, fourth bank contact to which 30 conductor #3 is connected over first digit code conductor 121, front contact and armature 120, back over conductor 128, front contact and armature 228, through the winding of slow-to-release relay 230, to battery. Relay 230 after an interval energizes and at armatures 231 and 232 disconnects the stepping magnet 240 from under control of the slow-operating relays 205, 210 and 215, and over front contacts and armatures 233 and 234 40 completes a locking circuit for itself independent of its original energizing circuit, from ground at the bank contact upon which wiper 251 is now resting. A branch of the locking circuit for relay 230 extends from the ground at bank contacts of wiper 251, through armatures 233 and 234 to the back contact of armature 241 and the winding of stepping magnet 240, to battery. Each time the stepping magnet 240 is energized it 45 interrupts its own circuit at its armature 241, thereby operating in the manner of a buzzer to rotate the wipers of the code sender. As a further result of the energization of slow-release relay 230 it completes a shunting circuit 50 extending around one side of relay 220, from grounded front contact and armature 235, armature 229 and its front contact, through one side of the winding of relay 220, thereby shunting out this relay, which upon 55 falling away opens the circuit at its armature 222 extending to the printing recorder PR at the telegraph office and at armature 221 it opens its locking circuit.

With relay 230 energized the stepping magnet 240 continues to operate in the manner 60

of a buzzer and rapidly rotates the wipers 250 to 253, inclusive, over their associated bank contacts until wiper 253 comes into engagement with bank contact 260. At the same time wiper 251 has reached bank contact 255 which is connected to the conductor extending to back contact of armature 219 of relay 225 which is still energized at this time. Consequently, slow-release relay 230 and the stepping magnet 240 are no longer 65 energized as they were over the grounded bank contacts over which wiper 251 has been rotated. After a short interval when relay 230 is completely deenergized it again closes the slow stepping circuit for the stepping magnet 240, at armatures 231 and 232, to place it under control of the slow-operating relays 205, 210 and 215. At grounded front contact and armature 235 the shunting circuit for relay 220 is opened and this relay is again 80 energized from battery through its winding, front contact and armature 227, bank contact 260 upon which wiper 253 is now resting, front contact and armature 226, to ground at armature 219 and its front contact. At armature 221 the locking circuit for relay 220 is completed when it energizes, and at armature 222 the circuit for the printing recording magnet PR is again closed each time relay 215 energizes. Accordingly, the second digit 85 of the code number is now transmitted to the telegraph office.

The stepping magnet 240 continues to rotate the wipers 250 to 252, inclusive, over their associated bank contacts under control 90 of the inter-action of relays 205, 210 and 215 until wiper 253 encounters the bank contact to which conductor #8 is connected. When this occurs the circuit for slow-release relay 230 is again completed over a circuit extending from battery through the winding of this relay, armature 228 and its front contact, conductor 128, armature 119 and its front contact, conductor 122, conductor #8 upon which wiper 253 is now resting, front contact and armature 226, to ground on armature 219 and its front contact. Relay 230 after an interval energizes and at armatures 231 and 232 and their back contacts removes the control of the stepping magnet 240 from the inter-action of relays 205, 210 and 215. At front contact and armatures 233 and 234 relay 230 completes the locking circuit for itself by way of wiper 251 and the grounded bank contact upon which it is now resting. At grounded front contact and armature 235 relay 220 is again shunted so as to disconnect the trunk line extending to the telegraph office and prevent the transmission of further impulses. A branch of the locking circuit of relay 230 again extends through the winding of the stepping magnet 240, to battery, and the stepping magnet thereby is energized and deenergized each time wiper 251 engages with a grounded bank contact. 100 105 110 115 120 125 130

It may be stated at this time that relay 230 has been made slow-to-release for the purpose of preventing it from deenergizing as the wiper 251 steps between the grounded bank contacts.

The wipers 250 to 253, inclusive, of the code sender CS are thereby rapidly rotated over their bank contacts until wiper 251 reaches its last bank contact 256, and as there is no ground potential upon this bank contact the slow-release relay 230 is no longer maintained energized and, likewise, the stepping magnet 240 has its circuit interrupted. At armatures 231 and 232 relay 230 upon falling away places the stepping magnet 240 again under control of the inter-acting slow relays 205, 210 and 215, and at armatures 233 and 234 a further point in the circuit of this relay and the stepping magnet is opened, at armature 235 the shunt circuit around relay 220 is disconnected and the relay 220 becomes energized immediately upon the wiper 252 being stepped onto its bank contact 258. The circuit for relay 220 now extends from battery through the resistance, the winding of the relay, front contact and armature 227, back contact 258, wiper 252 which is now resting on this bank contact, front contact and armature 226, to ground on front contact and armature 219. At armature 221 the locking circuit for relay 220 is again completed, while at armature 222 the circuit extending to the telegraph office printer is completed when relay 215 energizes. The stepping magnet 240 continues to advance the wipers of the code sender CS under control of inter-acting relays 250, 210 and 215.

At this time it will be noted that whereas the wipers 250 and 252 will be rotating over the bank contacts, the other wipers 251 and 253 will be rotating in an arc away from the bank contacts, so that they will not be effective. The printing recorder PR at the telegraph office is operated once each time the stepping magnet 240 advances its wipers one step, and this action continues until wiper 252 encounters the fifth bank contact to which conductor #4 is connected, whereupon, the circuit for slow-release relay 230 is again completed over conductor 128, armature 118 and its front contact, conductor 123, and the wiper 252 and the bank contact upon which it is now resting. Relay 230 again places the stepping magnet 240 under control of the series of grounded bank contacts over which wiper 250 is now rotating and it also completes its own locking circuit at armature 233, while at armature 235 it again shunts relay 220 so that further impulses will not be sent to the telegraph office. At armatures 231 and 232 the inter-action relays are disconnected from control of the stepping magnet 240 which operates in a buzzer-like action and continues to advance the wipers of the code sender until wiper 250

encounters bank contact 254, and as this bank contact is no longer grounded the relay 230 and the stepping magnet 240 will no longer be energized. Relay 230 upon falling away slowly, replaces the control of the stepping magnet back again to relays 205, 210 and 215 and their inter-action operation. The shunt circuit for relay 220 is removed at armature 235 and it again becomes energized and locks up in order to prepare the transmission of further impulses to the telegraph office.

The code number 384 which is individual to substation A has now been transmitted once over the conductors 223 and 224 to the printing recorder PR at the telegraph office, and in order to take care of any possible errors that may arise during the transmission of this number and also to take care of the fact that there may occasionally be dirty contacts on some of the contact springs, it is desirable that this code number be transmitted more than one time. It is for this purpose that the code cut-off switch CO is provided so that the code may be sent any number of times.

The operation of the code cut-off switch CO will now be pointed out in detail. As soon as the wiper 252 of the code switch CS, engages bank contact 257 it completes a circuit extending from grounded armature 219 and its front contact, armature 226 and its front contact, wiper 252 and bank contact 257 upon which it is now resting, conductor 143, through the winding of the stepping magnet 160 to battery, of the cut-off switch CO. As soon as wiper 252 steps off of bank contact 257 the circuit for stepping magnet 160 is opened and consequently, it retracts its armature and advances the wipers 162 and 163 forward one step onto their first set of bank contacts. As soon as wipers 250 and 252 step off of their last bank contact wipers 251 and 253 will engage their first bank contacts, the wiper 253 coming to rest upon bank contact 259. The code sender switch CS is now again in the same position it was at the time that its operation was initiated.

In the same manner as has been heretofore pointed out the code number 384 is again transmitted over the trunk line extending to the telegraph office to operate the printing recorder PR and again print the number of the code of the substation A. In a similar manner all of the relays for controlling the code switch CS are operated, as has been pointed out. After the code number has been transmitted the second time the wiper 252 again engages its bank contact 257, so that the stepping magnet 160 of the cut-off switch CO is energized the second time to rotate the wipers 162 and 163 onto their second bank contacts.

Referring again to the cut-off switch CO it will be noted that the wiper 162 requires

four steps to reach the bank contact 164, and from this it is seen that the code number will be transmitted four times to the telegraph office by code sender CS. The conductor attached to bank contact 164 may be attached to any one of the bank contacts which are accessible to wiper 162, so that the code may be transmitted to the telegraph office any number of times desired, although in actual practice it need not be transmitted more than three or four times. Each time the wipers of the code sender CS make one complete revolution over their bank contacts in transmitting a complete code number, the cut-off switch CO has its stepping magnet 160 energized once so that for each operation of the code sender the cut-off switch CO will operate one step.

With the wiper 162 of the cut-off switch CO resting on its bank contact 164 a circuit is completed from ground over the wiper and the bank contact, through the winding of relay 155, to battery. At armature 156 it prepares a locking circuit for itself and at armature 157 and its front contact it extends ground from this armature through the resistance 153, winding of slow-release relay 150, multiply connected bank contacts upon the fourth one of which wiper 163 is now resting, back contact and armature 161, and through the winding of the stepping magnet 160, to battery. Due to the inclusion of the resistance 153 in this circuit the stepping magnet 160 does not energize. However, the slow-release relay 150 energizes and at its armature and front contact 152 it short-circuits the resistance 153. At its grounded front contact and armature 151 relay 150 completes the locking circuit for relay 155 so that it will remain held up after wiper 162 is stepped off of bank contact 164. Stepping magnet 160 is now operated in a circuit including only the relay 150 and not the resistance 153 and it operates in the manner of a buzzer by interrupting its own circuit at its armature 161. It continues to rotate the wipers 161 and 163 in a forward direction over the multiply connected bank contacts until bank contact 165 is reached, whereupon the circuit for the stepping magnet 160 and slow-release relay 150 is permanently opened and the switch is now in its normal position.

As a further result of the energization of relay 155 it connects ground from its front contact and armature 158, over conductor 129, armature 116 and its front contact, through the winding of relay 110, to battery. Relay 110 upon energizing closes a locking circuit for itself from armature 107 over its armature 112, and at armature 111 and its back contact opens a point in the chain circuit 132 extending between the station relay groups SR. At armature 113 and its back contact relay 110 opens the locking circuit for relay 105 extending over armature 108 and this re-

lay releases. At armature 117 the locking circuit for the lower winding of relay 115 is interrupted and this relay restores. At armatures 118, 119 and 120 the circuit extending over conductor 128 and the multiple code 70 digit conductors 121, 122 and 123 is disconnected. Relay 105 which was released due to the opening of its locking circuit at armature 113 restores the chain circuit over conductor 132 and its armature 106 so that any other station relay group, such as SR6, which may have a code stored in the group of relays may seize the code sender CS to operate it and transmit the associated code to the telegraph office.

As a further result of the release of relay 110 and the opening of its armature 113 from its back contact, relay 140 is restored to normal and at its armature 141 and back contact again restores the battery to the multiple conductor 130 so that any other relays, such as 115, or other station relay groups may seize the code sender equipment. Relay 140 upon releasing opens the circuit of relay 145 at its armature 141, and relay 145 upon releasing in turn opens its armature 146 from grounded front contact, thereby interrupting the circuit for relay 225 which extended over conductor 142. Relay 225 upon restoring opens the armature 219 from its front contact thereby disconnecting the ground circuit from the slow inter-acting relays 205, 210 and controlling relay 215. At armature 227 the initial energizing circuit of relay 220 is opened, while at armature 228 the energizing circuit for relay 230 is likewise interrupted. The code sender switch wipers are now in their normal position as are also the group of relays which control them. The cut-off switch CO has likewise been restored to normal as well as all of the relays which control it and also the station relay group SR1.

The code sender CS is now in position to transmit another code which may be sent in by any other subscriber. The code number 384 which is individual to the substation A has been printed four times upon the tape at the telegraph office by the printing recording relay PR and an attendant at the telegraph office upon noting the code number will dispatch a messenger to the premises of the subscriber, who may receive a telegram message which is to be transmitted from the telegraph office or perform some other messenger duty.

From the foregoing detailed description of the operation it will be appreciated that only one code at a time may be transmitted by the code sender CS to the telegraph office, but should more than one subscriber in the system dial the number to seize its associated relay group, such as RG, the equipment will operate to engage with the associated station relay group SR and store the code in the group of relays, and immediately upon the transmission of this code the next preceding

station relay group SR will operate to seize the code sender CS and transmit its associated code number.

It occasionally happens due to accident or negligence on the part of an attendant at the telephone exchange that the wipers of the code sender CS are accidentally displaced, in this event when the equipment is seized in order to transmit a code to the telegraph office the code would be mutilated or an incorrect code would be transmitted. In order to take care of this the code sender switch CS is arranged to automatically restore its wipers to their normal positions whenever they are accidentally stepped off of the first step of the bank contact which is their normal position. When this occurs and wiper 251 is moved onto its second bank contact, ground is extended from this bank contact over the wiper, back contact and armature 228, through the winding of slow-release relay 230, to battery. Relay 230 upon energizing completes a locking circuit for itself at armature 233 in series with armature 234. A branch of the holding circuit of relay 230 extends by way of armature 241, through the winding of the stepping magnet 240, to battery. The stepping magnet 240, therefore, operates, in the manner of a buzzer by interrupting its own circuit at its armature 241 and rapidly rotates the wipers 250 to 253, inclusive, of the code sender CS in a forward direction over their associated bank contacts. When wiper 251 reaches bank contact 225 instead of picking up direct ground from the associated bank contact it completes a circuit through the conductor extending to the back contact and armature 219 and ground, and the rotary action continues. Upon wiper 251 stepping off of bank contact 256 wiper 250 will engage the first bank contact which is grounded and the stepping magnet 240 continues to be alternately energized and deenergized, stepping the wiper 250 and the other wipers across their bank contacts until wiper 250 steps off of the last bank contact in the arc, in which position the code sending switch CS is at normal, whereupon the circuit for the stepping magnet 240 and likewise the slow-release relay 230 is interrupted and relay 230 upon restoring its armature opens a further point in the circuit of the stepping magnet 240. The switch has now reached its normal position ready to receive a code number and transmit it to the telegraph office.

As the example illustrated and described comprises only a three digit system it will be appreciated that this may be changed to a large one by merely including additional sectors such as S, or it may be reduced if desired. Similarly the code signalling equipment may be arranged to transmit more or less than the number of digits indicated. For these reasons it is not desired to limit the invention to the exact embodiment as has been

described, but only to the extent of the appended claims.

What is claimed is:

1. In a combined telephone and signalling system, a central exchange, subscribers' lines connected to said exchange, means at said exchange controlled by a calling subscriber for establishing a telephone connection with any other subscriber's line, code signalling equipment at said exchange, code relays at the exchange individual to each subscriber's line, means controlled by a calling subscriber for operating the associated code relays to start the operation of said signalling equipment, a recording office connected to said exchange, and means controlled by said signalling equipment to transmit a code characteristic of said calling subscriber over the connection to said recording office.

2. In a combined telephone and signalling system, a central exchange having automatic switches over which telephone connections are established between subscribers' lines under control of a calling subscriber, code signalling equipment at said exchange, means controlled by a calling subscriber for establishing a connection over said automatic switches with said signalling equipment, means individual to each of said subscribers' lines for controlling said signalling equipment to generate a code characteristic of said calling subscriber, a telegraph office connected to said signalling equipment, and means controlled by said signalling equipment for transmitting said code a plurality of times to said telegraph office.

3. In a combined telephone and signalling system, subscribers' lines extending to an exchange having automatic switches over which the subscribers control the establishment of telephone connections, code signalling equipment at said exchange, code generating means individual to each subscriber's line, booster battery means accessible to said automatic switches, means controlled over any subscriber's line for establishing a signalling connection over said switches with said booster battery means, means responsive to said connection for extending said booster battery means back over said automatic switches to operate said code generating means individual to the calling line, and means responsive to the operation of said code generating means for controlling said code signalling equipment to transmit a code characteristic of said calling line.

4. In a combined telephone and signalling system, an exchange having automatic switches controlled by calling subscribers for establishing telephonic connections with called subscribers, code signalling equipment in said exchange, code generating means individual to each subscriber's line, booster battery means accessible to said subscribers' lines, means controlled by a calling sub-

scriber for controlling said automatic switches to establish a connection with said booster battery means and for operating said individual code generating means, a telegraph office connected to said signalling equipment, and means responsive to the operation of said code generating means for controlling said code signalling equipment to transmit a code characteristic of said calling line a plurality of times to said telegraph office.

5. In a combined telephone and signalling system, an exchange having automatic switches over which subscribers control the establishment of telephone connections, a holding relay accessible to said automatic switches, a relay group individual to each subscriber for initiating a code characteristic of said subscriber, code signalling equipment controlled by said individual relay groups, means responsive to the same control of said switches by any of said subscribers for operating said holding relay, and means responsive to the operation of said holding relay to control said relay group and operate said code signalling equipment only in accordance with the code of the calling subscriber.

6. In a signalling system, a plurality of lines each identified by a certain code designation, a plurality of control means, a series of selecting switches controlled by a line to select an idle one of said control means, code registering equipment, means responsive to the selection of one of said control means by a line for operating said registering equipment over said selecting switches to register the code designation of the line, and means for preventing the registration of the code of any other line while the code of the first line is being registered by said registering equipment.

7. In a combined telephone and signalling system, a central office, a plurality of telephone stations each connected to said central office, automatic switches at said office, means controlled from any telephone station for operating said automatic switches to establish a telephonic connection with any other telephone station, relay means accessible to said switches, a relay group individual to each of said telephone stations for generating a code designation characteristic of the station, a signal transmitter at said central office controlled by said relay groups, means controlled from any telephone station for operating said automatic switches to select said relay means and operate the same, means responsive to the operation of said relay means for operating the relay group individual to the telephone station over a circuit connection extending back over said automatic switches, and means responsive to the operation of said individual relay group for operating said signal transmitter to transmit

a code designation characteristic of the telephone station.

8. In a combined telephone and signalling system, a central office, a plurality of telephone stations each connected to said office, automatic switches in said office, relay means at said office, means controlled from any of said telephone stations for operating said automatic switches to establish a telephonic connection with any other telephone station or a signal connection with said relay means, a relay group individual to each of said telephone stations for generating a code characteristic of the associated station, signal transmitting means at said central office, means responsive to the connection of said telephone station with said relay means for operating the same to give an indication to said telephone station of such connection and for at the same time operating the relay group individual to the telephone station, and means responsive to the operation of said relay group for operating said signal transmitting means to transmit a signal characteristic of said telephone station.

9. In a telephone and signalling system, a central office, telephone substations each connected to said office, automatic switches in said office, means controlled from any of said substations for operating said automatic switches to connect with any other of said substations, signal initiating means common to said substations, code generating means individual to each of said substations for generating a code designation characteristic of the associated substation, signal transmission means connected to said code generating means, means controlled in the same manner from any of said stations for operating said automatic switches to connect with said common signal initiating means to operate the same, means responsive to the operation of said signal initiating means for operating said code generating means over a connection extending back over said automatic switches, and means responsive to the operation of said code generating means for controlling said signal transmission means to transmit the code designation of the calling telephone substation.

10. In a telephone and signalling system, a central office, telephone substations each connected to said office, automatic switches in said office, means controlled from any of said substations for operating said automatic switches to connect with any other of said substations, signal initiating means common to said substations, code generating means individual to each of said substations for generating a code designation characteristic of the associated substation, signal transmission means connected to said code generating means, means controlled from any of said stations for operating said automatic switches to connect with said common signal initiating

means to operate the same, means responsive to the operation of said signal initiating means for operating said code generating means, and means responsive to the operation of said code generating means for controlling said signal transmission means to transmit the code designation of the calling telephone substation.

11. In a telephone and signalling system, 10 a central office, a plurality of telephone substations connected to said office, automatic switches in said office, means controlled from any of said substations for operating said automatic switches to establish a telephone 15 connection with any other of said substations, signal initiating means common to said substations, signalling equipment in said office for transmitting signals of a calling substation, means controlled in a similar manner 20 by any of said substations for operating said automatic switches to establish a connection with said signal initiating means to operate the same, means responsive to the operation of said signal initiating means for operating 25 said signalling equipment over a connection extending back over said automatic switches, and means responsive to the operation of said signalling equipment for transmitting a code designation characteristic of the calling substation.

12. In a combined telephone and signalling system, a central exchange having substation lines extending thereto and terminating in automatic switches, code signalling equipment in said exchange, means controlled from any substation for operating the automatic switches to establish a telephone connection with any other substation or for connecting with said code equipment, means in said code 40 equipment responsive to the connection of a substation line therewith for generating a code indicative of the substation, and means for transmitting said code over a different connection from said exchange.

45 13. In a combined signalling and telephone system, a central exchange having substation lines extending thereto and terminating in automatic switches, code signalling equipment in said exchange, means controlled from any substation in accordance with the number of any other desired substation for operating the automatic switches to establish a telephone connection therewith, means controlled from any substation in accordance 50 with a number common to all of said substations for establishing a connection over said automatic switches with said signalling equipment, means in said equipment responsive to the connection of any substation there- 55 with for generating a code individual to only said substation, and means for transmitting said individual code from said exchange.

60 14. In a combined telephone and signalling system, a central exchange having substation lines extending thereto and terminating

in automatic switches, code signalling equipment in said central exchange, means controlled at a calling substation for operating the automatic switches in accordance with the number of a called substation to establish a telephonic connection therewith, said means operative to control the automatic switches in accordance with a number common to all of said substations to establish a connection with said signalling equipment, 70 means in said signalling equipment responsive to the connection of a substation therewith for generating a code number individual only to that substation, and means operative to transmit said code number from said exchange regardless of whether the calling substation has been released from its connection with the signalling equipment,

75 15. In a combined telephone and signalling system, a central exchange having substations connected thereto, code signalling equipment in said exchange, means in said exchange controlled by a calling substation for establishing a telephonic connection with any desired called substation, said means controlled in 80 the same manner by any calling substation for establishing a connection with said signalling equipment, means for indicating to the substation when such signalling connection is established whereby the connection 85 may be released immediately, means in said signalling equipment for generating a code corresponding to the calling substation upon the connection therewith, and means for then transmitting said code independently of the 90 continued connection of the calling substation with said equipment.

100 16. In a telephone system in which a signalling system is incorporated, a central exchange, substations connected to said exchange and each having an impulse sender thereat, code signalling equipment at said exchange, means responsive to the operation of the impulse sender at a calling substation in accordance with the designation of a 105 called substation for establishing a telephone connection therewith, means responsive to the operation of the impulse sender at a calling station in accordance with a designation common to all of said substations for establishing a connection with said signalling equipment, means in said signalling equipment responsive to the connection of a substation therewith for generating a code individual only to that substation, means for 110 indicating to the connected substation that the connection with the signalling equipment is established so that the connection may be released if desired, and means in said signalling equipment for transmitting the code of 115 the calling substation from said central exchange.

120 17. In the combination of a telephone system and a signalling system, a central exchange, substation lines extending to said 125

exchange, a series of automatic switches in said exchange controllable by said substation to establish telephone connections between them, code signalling equipment in said exchange, means for controlling the automatic switches in the same manner by all of the substations for establishing a connection with said signalling equipment, a circuit connection extending from the connected 10 substation line to said code signalling equipment exclusive of said automatic switches, and means in said signalling equipment controlled over said circuit connection for initiating the generation of a code individual 15 only to the connected substation.

18. In the combination of a telephone system and a signalling system, a central exchange, substation lines terminating in said exchange, automatic switches controlled by 20 any calling substation for establishing a telephone connection with any called substation, code signalling equipment in said exchange, a circuit connection extending from the terminating end of each substation line to said 25 signalling equipment, means for controlling the automatic switches in the same manner by any calling substation to extend a connection to said signalling equipment, means responsive to said connection for energizing 30 said circuit connection from the terminating end of the substation to initiate the generation of a code by said signalling equipment which is individual only to the connected substation, and means in said signalling 35 equipment for transmitting said code.

In witness whereof, I hereunto subscribe my name this 2d day of July, A. D. 1930.

EDWARD S. PETERSON.
